(57) **CLAIM**

The ornamental design for an electroluminescent toy safety light, as shown and described.

DESCRIPTION

FIG. 1 is a right side elevational view of an electroluminescent toy safety light showing my new design, with the opposite side being a mirror image, and with the wire encased in the plastic sleeve shown broken away to indicated indeterminate length;

FIG. 2 is a top plan view thereof, with the bottom being a mirror image;

FIG. 3 is a perspective view thereof;

FIG. 4 is a sectional view taken along line 2—2 in FIG. 2, and,

FIG. 5 is a front elevational view thereof.
